UNITED STATES PATENT OFFICE.

LOUIS HILLEBRAND, OF PHILADELPHIA, PENNSYLVANIA, ASSIGNOR OF
ONE-HALF TO DANIEL WOLF, OF SAME PLACE.

HINGE.

SPECIFICATION forming part of Letters Patent No. 393,305, dated November 20, 1888.

Application filed June 29, 1888. Serial No. 278,511. (Model.)

To all whom it may concern:

Be it known that I, LOUIS HILLEBRAND, a citizen of the United States, residing in the city and county of Philadelphia, State of Pennsylvania, have invented a new and useful Improvement 5 in Hinges and Hasps, which improvement is fully set forth in the following specification and accompanying drawings.

My invention consists in the construction of 10 a hinge or hasp having a leaf, one end whereof is bent or curled into the form of a cylinder constituting an axis, whereby a pintle as such is dispensed with and a strong and serviceable hinge is produced.

15 The invention also consists in recessing the leaf to receive a knuckle or ear which is secured to the attaching-plate and embraces the cylindrical portion or axis of the leaf, thus firmly retaining said leaf in position.

20 Figure 1 represents a face view of a hinge embodying my invention. Fig. 2 represents an end view thereof. Fig. 3 represents a section on line *x* *x*, Fig. 1. Fig. 4 represents a face view of a hasp embodying my invention.

25 Fig. 5 represents a section on line *y* *y*, Fig. 4. Fig. 6 represents a face view of the leaf thereof.

Similar letters of reference indicate corresponding parts in the several figures.

Referring to the drawings, A, Figs. 1 and 2, 30 represents one of the leaves of a hinge, and B represents the other leaf or bottom attaching-plate thereof.

The leaf A, which is constructed of sheet metal, has its inner or axial end bent into the 35 form of a cylinder, C, which is embraced in part by a knuckle or ear, D, the latter being riveted or otherwise secured to the plate B. The portion of the leaf A adjacent to the ear D is cut out or recessed within its side edges, 40 as at *a*, to receive the wall of the ear D and permit said leaf to rotate or turn on said ear, it being evident that the ear prevents disconnection of the leaf and plate.

It will be seen that the leaf A may be turned 45 or swung on the plate B, the cylinder C forming the axis of said leaf and the ear D forming the bearing for said axis; it being also seen that a pintle or rod usually employed in a hinge

and passed through the knuckles thereof is dispensed with and a strong and durable and serviceable hinge is produced. The same has no lost motion between the leaf and plate, owing to the cylinder fully occupying the inner wall of the knuckle or ear and the recess of the same.

In Figs. 4, 5, and 6 the improvement is shown 50 as applied to a hinged lock-hasp, the swinging part of the hasp corresponding to the leaf A of the hinge and having the cylindrical axis C and bearing D therefor, the hasp being also provided with a spring for throwing out the 55 part A, when so desired. In this case the leaf is provided with two recesses, *a* *a*', with a neck, *c*, between them, as seen in Figs. 4 and 6, and the ear or knuckle D has a slot to allow the leaf to revolve the required extent, limited 60 by said neck which enters the slot and acts as a stop against the wall thereof.

Having thus described my invention, what I claim as new, and desire to secure by Letters Patent, is—

1. A sheet-metal hinge having a base or attaching plate, a separate arch-shaped cover or ear fastened thereto, and a leaf with a curled end, said end being encircled by said cover or ear, the parts being combined substantially 75 as described.

2. A hinge or hasp consisting of a leaf with a bent or cylindrical end portion and a slot parallel to said cylindrical end, an attaching-plate, and a separate knuckle or ear suitably secured 80 to said attaching-plate, said parts being combined substantially as described.

3. A sheet-metal hinge or hasp consisting of an attaching-plate, a leaf with a cylindrical end portion and having slots forming a neck 85 between the same, and an ear secured to said plate and having a portion of one of its walls passing through said slots in the leaf, the neck of the leaf working in a slot in said ear, said parts being combined substantially as and for 90 the purpose set forth.

L. HILLEBRAND.
